(57) **CLAIM**

The ornamental design for a bronchoscope, as shown and described.

DESCRIPTION

FIG. 1 is a front perspective view of a bronchoscope according to an embodiment of the present invention.

FIG. 2 is a front view of the bronchoscope of FIG. 1.

FIG. 3 is a rear view of the bronchoscope of FIG. 1.

FIG. 4 is a left side view of the bronchoscope of FIG. 1.

FIG. 5 is a right side view of the bronchoscope of FIG. 1.

FIG. 6 is a top view of the bronchoscope of FIG. 1; and, FIG. 7 is a bottom view of the bronchoscope of FIG. 1. The drawings are shown with a break, and the appearance of any portion of the article between the break lines forms no part of the claimed design.
